UNITED STATES PATENT OFFICE.

RAYMOND E. BEEGLE, OF EAST ST. LOUIS, ILLINOIS, ASSIGNOR OF ONE-HALF TO WIL-
LIAM J. STEINBREDER, OF ST. LOUIS, MISSOURI.

CLAMPING DEVICE.

Application filed October 23, 1924. Serial No. 745,405.

This invention relates generally to clamp-
ing devices, and particularly to a clamping
device which may be associated with flexi-
ble tubular articles, such as rubber hose, for
5 the purpose of clamping said rubber hose to
such articles as coupling members, ferrules,
etc. Also, the clamping device disclosed in
the present application may be used to clamp
radio ground wires to a water pipe or like
10 article.

Briefly stated, my improved clamping de-
vice comprises a circular band which is ar-
ranged to surround the article it is desired
to clamp. The circular band mentioned is
15 provided with one or more projecting por-
tions, which are capable of being bent in
such manner that the diameter of the circu-
lar band will be reduced by such bending
operation, whereby the article surrounded
20 by said circular band will be tightly gripped
thereby.

Fig. I is a side elevation of one form of
my improved clamping device.

Fig. II is a fragmentary view showing the
25 clamping device illustrated in Fig. I after
same has been contracted.

Fig. III is a section on line III—III of
Fig. I.

Fig. IV is a side elevation of another
30 form of my invention.

Fig. V is a fragmentary view of the
clamping device shown in Fig. IV after
same has been contracted.

Fig. VI is a section on line VI—VI of
35 Fig. V.

Fig. VII is a fragmentary view showing
the manner of attaching a wire to my im-
proved clamping device when said clamping
40 device is used to attach a radio ground wire
to a grounded article, such as a water pipe.

Fig. VIII is another form of my inven-
tion.

Fig. IX is a fragmentary view of the
clamping device shown in Fig. VIII after
45 same has been contracted.

Fig. X is still another form of my inven-
tion.

Fig. XI is a section on line XI—XI of
Fig. IV.

50 In Figs. IV, V and VI of the drawings,
A designates my improved clamping device,
which comprises an annular band B com-
posed of a pair of members C and D. The
members C and D are preferably formed
55 from strips of resilient material, which are

of some considerable width, as shown in
Fig. VI, and said members are provided
with strengthening ribs E which extend cir-
cumferentially of said members to add ri-
gidity thereto. Formed at an end of the 60
member D is a projecting portion 1, which
comprises a pair of legs 2 and 3 formed in-
tegral with said member D, said legs being
arranged at an angle to each other so that
an approximately V-shaped space is pro- 65
vided between said legs. By referring to
Fig. IV it will be noted that the leg 2 of
the projecting portion 1 is offset from the
wall of the member D. This arrangement
results in an abutment 4 being formed, 70
which is intended for a purpose to be here-
inafter set forth. It will also be noted from
the view mentioned that the rib E asso-
ciated with the member D is extended to a
point where a portion D' of said rib is asso- 75
ciated with the leg 2. The leg 3 of the ex-
tended portion 1 is also provided with a rib
which is designated by the reference char-
acter 5. Located at an end of the member
C of the band B is a projecting portion 6, 80
comprising a single leg, said leg being pro-
vided with a reinforcing rib 7. Formed in-
tegral with the leg 6 is a pair of ears 8,
there being one of these ears located at each
side marginal edge of said leg. 85

Arranged at the end of the member D op-
posite to the end thereof provided with the
projecting portion 1 is a plurality of aper-
tures 9, and arranged at the end of the mem-
ber C opposite to the end provided with the 90
projecting portion 6 is a hook 10. The end
portion of the member C which is provided
with the hook 10 is offset from the wall of
said member C and is reduced in width with
relation to said wall of said member C. 95
Also that portion of the member D which is
provided with the apertures 9 is channel-
shaped in cross section, as shown in Fig. XI,
whereby the inner portion of the hook 10
will be flush with the inside face of the band 100
B when the members D and C are connected
together. It is apparent from the forego-
ing that the diameter of the band B may be
varied by inserting the hook 10 in the vari-
ous apertures 9, it being plain that the band 105
B would be of much greater diameter when
the hook 10 is in an aperture adjacent to the
end of the member D than it would when
said hook is in an aperture removed in-
wardly from the end of said member D. 110

11 designates a clamping means for securing a wire to the clamping device A, said clamping means 11 being utilized when the clamping device is employed to attach a radio ground wire to a grounded article, such as a water pipe. The clamping means 11 is produced by cutting a pair of slits 12 and 13 in the member D of the band B. The material 14 of the member D which is located 10 above the slit 12 and the material 15 which is below the slit 13 is bent inwardly, and the material 16 which is located between said slits 12 and 13 is bent outwardly. This provides a space between the bent portions of the member D through which the wire 17 is passed, and when the band B is drawn tightly about an article, such as a water pipe, it is plain that these bent portions will be caused to grip said wire, whereby it will be tightly held, 20 and because the band B is made of metallic material an electrical connection will be made between said wire and the article which is surrounded by said band.

In describing the use of my improved 25 clamping device it will be assumed that it is being used to clamp a section of rubber hose to a ferrule. The rubber hose is slipped over the end of the ferrule in the usual manner and the band B of my device is caused to 30 encircle said hose at the point where it encloses said ferrule. If the diameter of the band B is not such that said band fits close to the circumferential face of the hose, said band may be adjusted by moving the hook 35 10 into an aperture 9, which will cause said band to have the proper diameter. The projecting portion 6 of the member C is, of course, arranged within the approximately 40 V-shaped space between the legs of the projecting portion 1, as shown in Fig. IV, and said assembled projecting portions are subjected to downward pressure by being hammered, or in any other suitable manner, whereby said projecting portions are 45 brought to the position in which they are shown in Fig. V. This will have the effect of reducing the diameter of the band so that it will tightly grip the article which it surrounds, and it will also securely lock the 50 ends of the members C and D together.

After the projecting portions 1 and 6 have 55 been bent as described, the ears 8 associated with the projecting portion 6 will be bent over as shown in Fig. VI, so that they embrace the leg 2 of the portion 1, whereby accidental disconnection of said portions is 60 prevented. It will be noted that when the parts are assembled as described, the curved end C' of the member C will abut against the abutment 4. This will have the effect of preventing longitudinal movement of the 65 portions 1 and 6 relative to each other in an inward direction, the interlocked portions preventing longitudinal movement of said portions in an outward direction. When

the portions 1 and 6 are interlocked as described, the ribs formed on said portions will rest within each other, as shown in Fig. VI.

When the clamping device is used to 70 clamp a radio ground wire to a water pipe or similar article, it is applied in exactly the same manner as just described.

In the form of my device shown in Figs. I, II and III the band B^a is provided with a 75 plurality of projecting portions 1^a and 1^b which are similar to the projecting portion 1 of the form of the device already described, said portions 1^a and 1^b each comprising a pair of legs arranged at an angle 80 to each other to provide an approximately V-shaped space therebetween. This form of my device is also provided with a projecting portion 6^a similar to the projecting portion 6 described, and said projecting portion 6^a is provided with integral ears 8^a. By providing the band B^a with a plurality of projecting portions 1^a and 1^b the diameter of 85 said band may be adjusted to fit articles of different sizes, it being plain that when the portion 6^a is inserted into the projecting portion 1^b the band will have much greater diameter than if said portion 6^a were inserted into the projecting portion 1^a. The band B^a is clamped on an article in the same 90 manner as is the band illustrated in Fig. IV, the projecting portions 1^a and 1^b being bent downwardly to contract said band and lock the ends thereof together, as shown in Fig. II. After the portions 1^a and 1^b are bent 95 100 downwardly as described, the ears 8^a are bent to positions where they engage said bent portions to retain said bent portions in the positions to which they have been moved. It is apparent that in addition to the adjustable feature the presence of the pair of 105 projecting portions 1^a and 1^b will increase the amount of contraction obtained when said projecting portions are bent downwardly.

In Figs. VIII and IX I show another form of my invention in which a single projecting portion 1^c is employed. It will be noted that the band B^c is not separable at the projecting portion as is the case with the 110 two forms of my invention already described, but the pair of legs which comprise said projecting portion are formed as unbroken parts of the band. The band shown in Fig. VIII is provided with a hook 10^c 115 at one of its ends and a plurality of apertures 9^c at its other end, so that said ends of said band may be adjustably connected together, this arrangement being similar to the adjustable feature shown in Fig. IV and 120 already described. The band B^c is provided with integral ears 8^c which are adapted to be bent to retain the projecting portion 1^c 125 in its bent position.

Fig. X shows a device comprising a band 130

B^d provided with a projecting portion 1^d composed of a leg 2^d and a leg 3^d arranged at an angle to each other. Arranged adjacent to the end of the band opposite to the end having the projecting portion 1^d is a plurality of openings, there being a number of notches 20 at one side marginal edge of said band and a plurality of enclosed apertures 21 adjacent to the opposite side marginal edge of said band. The leg 2^d is provided with a pair of spaced-apart projections 22 which are adapted to be inserted into the openings 20 and 21. In the use of the device shown in Fig. X the projections 22 on the leg 2^d are inserted into the openings, which will cause the band to have the proper diameter. The projecting portion 1^d is then bent downwardly, whereby the ends of said band are drawn together, thus reducing the diameter of said band and causing same to grip tightly the article which it is desired to clamp.

It is apparent that in the use of all of the forms of the device shown and described, the bands may be slipped over the end of the article to be clamped or the ends of said band may be separated from each other and said band caused to surround the article to be clamped by being moved transversely relative to said article.

I claim:

1. A clamping device comprising a flexible band shaped to produce an annular member, and a projecting portion on said band, said projecting portion comprising a pair of legs arranged at an angle to each other to provide an approximately V-shaped space therebetween, and said projecting portion being adapted to be bent to cause said annular member to be contracted, said band being provided with an abutment with which a portion of said band contacts when said projecting portion has been bent to contract said annular member.

2. A clamping device comprising a flexible band shaped to produce an annular member, a projecting portion on said band, said projecting portion being adapted to be bent to cause said annular member to be contracted, and means whereby the diameter of said annular member may be regulated.

3. A clamping device comprising a flexible band shaped to produce an annular member, a projecting portion on said band, said projecting portion being adapted to be bent to cause said annular member to be contracted, and means whereby the diameter of said annular member may be regulated, said means comprising an end portion of said band movable into various openings in an adjacent portion of said band.

4. A clamping device comprising a flexible band shaped to produce an annular member, a projecting portion on said band, said projecting portion being adapted to

be bent to cause said annular member to be contracted, and means whereby the diameter of said annular member may be regulated, said means comprising a hook formed at an end of said band and movable into various openings in an adjacent portion of said band.

5. A clamping device comprising a flexible band shaped to produce an annular member, a projecting portion on said band, said projecting portion being adapted to be bent to cause said annular member to be contracted, and means comprising a pair of integral ears on said band capable of being bent to embrace said bent projecting portion whereby said projecting portion is retained in such bent position.

6. A clamping device comprising a flexible band shaped to produce an annular member, a projecting portion on said band, said projecting portion being adapted to be bent to cause said annular member to be contracted, and means comprising an ear on said band capable of being bent to embrace said bent projecting portion whereby said projecting portion is retained in such bent position.

7. A clamping device comprising a flexible band shaped to produce an annular member, a projecting portion at an end of said band, said projecting portion comprising a pair of legs arranged at an angle to each other to produce an approximately V-shaped space between said legs, and a projecting portion at the other end of said band, the last mentioned projecting portion being adapted to be inserted into the V-shaped space between the legs of the first mentioned projecting portion and said projecting portions being adapted to be bent to cause said annular member to be contracted.

8. A clamping device comprising a flexible band shaped to produce an annular member, a projecting portion at an end of said band, said projecting portion comprising a pair of legs arranged at an angle to each other to produce an approximately V-shaped space between said legs, a projecting portion at the other end of said band, the last mentioned projecting portion being adapted to be inserted into the V-shaped space between the legs of the first mentioned projecting portion and said projecting portions being adapted to be bent to cause said annular member to be contracted, and means on the last mentioned projecting portion whereby said projecting portions are retained in the positions to which they are bent.

9. A clamping device comprising a flexible band shaped to produce an annular member, a projecting portion at an end of said band, said projecting portion comprising a pair of legs arranged at an angle to each other to produce an approximately V-

shaped space between said legs, a projecting portion at the other end of said band, the last mentioned projecting portion being adapted to be inserted into the V-shaped space between the legs of the first mentioned projecting portion and said projecting portions being adapted to be bent to cause said annular member to be contracted, and means comprising integral ears on the last mentioned projecting portion whereby said projecting portions are retained in the positions to which they are bent.

10. A clamping device comprising a flexible band shaped to produce an annular member, said band being composed of a pair of members adjustably secured together whereby the diameter of said annular member may be varied, a projecting portion at an end of said band, said projecting portion comprising a pair of legs arranged at an angle to each other to produce an approximately V-shaped space between said legs, a

projecting portion at the other end of said band, the last mentioned projecting portion being adapted to be inserted into the V-shaped space between the legs of the first mentioned projecting portion and said projecting portions being adapted to be bent to cause said annular member to be contracted, and means comprising integral ears on the last mentioned projecting portion whereby said projecting portions are retained in the positions to which they are bent.

11. A clamping device comprising a flexible band shaped to produce an annular member, and a projecting portion on said band, said projecting portion being adapted to be bent to cause said annular member to be contracted, said band being provided with portions adapted to grip a wire.

In testimony that I claim the foregoing I hereunto affix my signature.

RAYMOND E. BEEGLE.
